UNITED STATES PATENT OFFICE.

NAPOLEON R. THIBERT, OF WORCESTER, MASSACHUSETTS.

LOCKING DEVICE FOR CAPS OR PLUGS.

Application filed February 25, 1924. Serial No. 694,869.

To all whom it may concern:

Be it known that I, NAPOLEON R. THIBERT, a citizen of the United States, residing at Worcester, in the county of Worcester and 5 State of Massachusetts, have invented a new and useful Locking Device for Caps or Plugs, of which the following is a specification.

This invention relates to a device for preventing the accidental removal of the cap or plug of a receptacle such as a grease cup.

The principal objects of the invention are to provide a simple and inexpensive construction for this purpose which will prevent the vibration of running machinery, particularly locomotives, from jarring such a cap or plug loose so that it may be lost; to provide means whereby the application of 20 a wrench to the plug or cap will be prevented except when the device is unlocked, thereby avoiding the marring and breaking of the device by unskilled operators; to provide means whereby the locking is secured 25 in a very simple and convenient manner and the parts cannot become detached and lost.

Reference is to be had to the accompanying drawings, in which

Fig. 1 is a plan of a locking device according to this invention applied to a grease cup or plug and shown partly in section;

Fig. 2 is a sectional view through the center of the same with the parts in locked position; and

Fig. 3 is a side view showing the position of the parts when unlocked.

I have shown the invention as applied to a grease cup 10 although it is applicable to any other receptacle. This is arranged with 40 an inside thread for receiving a closing plug 11. This plug is made in general in the usual way with a hexagonal or other non-circular head 12 for the reception of the wrench for use in screwing it down to closed 45 position.

On the top of this head 12 I place a cap 13 having a cylindrical flange 14 extending down far enough so that it will cover and conceal the hex nut 12 when it is lowered. 50 This cap is provided with a plate 15 on top secured to the cap in any desired way and provided at the ends with two integral pins 16 located at right angles to it and projecting down through corresponding perforations provided in the nut 12. These perforations are made large enough so that these

pins can slide easily up and down on the nut. The lower ends of these pins are sharpened and slanted off at an angle, as indicated. These sharp edges are intended 60 to engage the top edge of the grease cup on its inner corner. They slant outwardly and upwardly so as to secure a positive grip on this surface. These pins are made integral with the plate 15 so that the two pins and 65 plate can be made out of a single piece of steel bent up to the shape indicated and finished as desired.

The parts above described are connected by a locking bolt 17. This bolt is provided 70 with a cylindrical shank passing freely through holes in the center of the plate 15 and cap 13. On the bottom of the cap I provide a circular wire 19 extending into a groove in the bolt 17 to prevent longitudinal 75 motion of the bolt with respect to the cap 13 and to allow the bolt to be rotated freely. A washer 18 is shown above it. The center of the top of the plug 11 is perforated and threaded to receive the bolt so that the bolt 80 can screw down into it from the position shown in Fig. 3 where it is unlocked, to the position shown in Fig. 2, where it is locked. The lower end of the bolt is headed over at 20 so that the bolt cannot be 85 withdrawn from the plug.

Starting with the parts in the position shown in Fig. 3 with the nut 12 screwed down the device is locked by turning the bolt 17 by hand or wrench down as far as 90 it will go. A strong man can turn it down far enough so that it will force the two pins 16 down into contact with the upper edges of the neck of the receptacle 10 enough to prevent the dislodgment of the nut readily. 95 But in order to lock it properly a wrench has to be applied to it and the pins forced down until they actually cut into the edge of the neck of the receptacle. In that way the nut is positively locked and it cannot be disengaged by the application of a wrench. If a wrench could be applied to the nut 12 a strong man could turn it possibly and scrape the pins along the surface of the receptacle 10 or otherwise injure the parts. 100 It is to avoid this that the collar 14 is used. It will be seen that this covers so much of the nut 12 that it is practically impossible for an unexperienced operator to apply a wrench to it to do any damage when it is 110 locked down. At the same time when everything is open as shown in Fig. 3 there is no

obstacle to the application of the wrench and the tightening up of the plug as much as desired.

It will be observed that as the bolt 17 is turned, the cap 13 and associated parts 13 and 15 necessarily move up with it so that the nut is exposed as shown in this figure. At the same time when the headed end of the bolt is raised to contact with the inner wall of the plug 11 the parts cannot be separated any further and if the plug is taken out and put one side there is no way in which any of the parts associated with it can become lost except by actual destruction of the parts.

In this way it will be seen that the device is capable of locking the plug with sufficient force to prevent its jarring loose under the most severe practice. Although the nut cannot be reached to attempt to unscrew it, while the locking device is in operation, yet, when it is withdrawn the nut is exposed so that the operator has full advantage of it. At the same time the parts of the device are permanently fixed together so that they cannot become separated in any way or lost and yet the cost of manufacture is very low.

I have shown this as applied to a closing plug but of course a closing cap having an internal instead of an external screw thread can be locked in accordance with the same principle. Although I have illustrated and described only one form of the invention I am aware of the fact that modifications can be made therein by any person skilled in the art without departing from the scope of the invention as expressed in the claims. Therefore, I do not wish to be limited to all the details of construction herein shown and described or to a plug having an external screw thread but what I do claim is:—

1. The combination with a screw threaded head for closing a receptacle or the like, of a plate mounted thereon and having pins projecting through the top of said head and means for moving said pins longitudinally through said head for the purpose of locking it against rotation.

2. The combination with a screw threaded head for closing a receptacle or the like, of a plate mounted thereon and having pins projecting through the top of said head, and means for moving said pins longitudinally through said head, said pins being sharpened on their extreme ends at an angle whereby when they engage the edge of the upper end of the mouth of the receptacle they will prevent rotation of the head.

3. The combination with a screw threaded head for closing a receptacle or the like, of a plate mounted thereon and having pins projecting through the top of said head adapted to come into contact with the upper

edge of the mouth of the receptacle, means for moving said pins longitudinally through said head for the purpose of locking it against rotation, and means for preventing the separation of the plate from the head. 70

4. In a device of the character described, the combination with a receptacle closure having a non-circular end by which it is adapted to be operated by a wrench, of a cap movably mounted over said end and having a flange adapted to conceal the non-circular surface to prevent application of the wrench, said cap having pins slidably projecting through the closure, means for moving the cap and pins in an axial direction with respect to the closure, and means for permanently preventing the detachment of the cap from the closure. 80

5. In a device of the character described, the combination with a closure for a receptacle having a non-circular end by which it is adapted to be operated by a wrench, of a cap movably mounted over said end and having a flange adapted to conceal the non-circular surfaces to prevent application of the wrench, said cap having pins slidably projecting through the closure into contact with the mouth of the receptacle, and means for moving the cap and pins in an axial direction with respect to the closure. 90

6. In a device of the character described, the combination with a screw threaded closure for the mouth of a receptacle or the like, said closure having a shape at the top adapting it to be operated by a wrench and provided with a screw threaded perforation at the center, of a bolt located in said screw threaded perforation and adapted to move up and down in it, a cap over the top of the closure having a non-threaded smooth perforation therethrough, whereby the bolt can turn therein, means for causing the cap to move axially with the bolt, and a pair of pins projecting down from said cap through said closure. 100

7. In a device of the character described, the combination with a screw threaded closure for the mouth of a receptacle or the like, said closure having a shape at the top adapting it to be operated by a wrench to screw it into place and provided with a pair of diametrically opposite perforations therethrough and with a screw threaded perforation at the center, of a bolt located in said screw threaded perforation and adapted to move up and down in it, a cap over the top of the closure having a non-threaded smooth perforation therethrough, whereby the bolt can turn therein, means for causing the cap to move axially with the bolt, and a pair of pins projecting down from said cap through said perforations in the closure preventing the cap from turning with the bolt. 115

8. In a device of the character described, 130

the combination with a screw threaded closure for the mouth of a receptacle or the like, said closure having a shape at the top adapting it to be operated by a wrench and provided with a screw threaded perforation at the center, of a bolt located in said screw threaded perforation and adapted to move up and down in it, a cap over the top of the closure having a non-threaded smooth perforation therethrough, whereby the bolt can turn therein and provided with means for causing the cap to move axially with the bolt, and a pair of pins projecting down from said cap through said closure, said

bolt being headed over within said closure 15 to prevent its detachment therefrom.

9. In a receptacle cover, the combination with a head having a screw thread for connection with a receptacle and having a polygonal head, of a cap over the head, a 20 plate fixed on the cap having integral pins projecting down through the cap, and means carried by the head for adjusting the cap to bring the pins into and out of action.

In testimony whereof I have hereunto 25 affixed my signature.

NAPOLEON R. THIBERT.
